The ornamental design for a kitchen rack as shown and described.

DESCRIPTION

FIG. 1 is a front, right, and top perspective view of a kitchen rack, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is a partial enlarged view of an area labeled 8 in FIG. 1 comprising an adjusting nut.

The dash-dash broken lines shown in the drawings are included for the purpose of illustrating portions of the kitchen rack that form no part of the claimed design. The dot-dash broken lines depict reference to the enlargement and form no part of the claimed design.

The wavy broken line sets along the lengths of the support wires depict symbolic breaks only and form not part of the claimed design. The appearance of any portions between the symbolic break lines forms no part of the claim.
